TOOL FOR RESERVICING SPRINGS
EQUIPPED WITH SPRING-COVERS

Warren F. Eisenhauer, Cambridge, Mass., assignor to Anderson Manufacturing Company, Cambridge, Mass., a corporation of Massachusetts

Application June 20, 1934, Serial No. 731,556

11 Claims. (Cl. 184—105)

This invention relates to the servicing of multiple leaf springs when equipped with spring-covers. This servicing is termed "re-greasing" although it is not a greasing or lubrication of the kind that causes excessive flexibility of the springs but rather an application to the springs of a graphite compound which, while functioning as a lubricating grease, is especially prepared for maintaining a controlled interplate friction, thus stabilizing the action of the springs and maintaining riding comfort. One large use of spring-covers which requires servicing of the enclosed springs from time to time in order to maintain a predetermined spring action is found in the motor car industry.

If the spring-cover equipment is installed by the car manufacturer the spring is serviced by thoroughly covering each separate plate, particularly over their contact areas, preferably with a graphite grease compound that acts as a stabilizer and packing after final assembly. If the springs are to be initially serviced and covered by the car owner then the plates of each spring are separated for receiving the stabilizing compound between them. Just before applying the covering materials more of the compound is applied to the exposed surfaces of the spring. The spring-cover holds this compound in place and keeps out dirt and water, the latter being very detrimental to satisfactory spring action. The bulk of present day spring-covers are metallic, although flexible materials are still in use to some extent, and usually a duck or canvas liner is wrapped about the packed spring before the cover is applied.

During the years that spring-covers have been used it has been found that certain conditions make it advisable to re-service the spring. Reservicing may be accomplished by removing the covering material and re-packing the spring plates with the stabilizing compound or the plates may be repacked through the cover and liner without removal from the spring by the use of the service tool of this invention.

It is highly important that the greasing compound for re-servicing be introduced in such a manner that it will reach the spring inside the liner and spread between the plates. Care must be taken that the compound is not spread merely between the liner and the cover for then its efficacy is substantially nullified.

The principal object of the invention is to provide a service tool adapted to receive a fitting for use with a pressure grease gun enabling any service station operative properly to re-service mul-

5
tiple leaf springs equipped with any type of spring-cover. A further object of the invention is to provide a small, light re-servicing tool that may be easily manipulated as a hand tool by an unskilled operator with wholly satisfactory results.

To the accomplishment of these objects and such others as may hereinafter appear the invention comprises a hand tool having special features enabling transmission of the greasing compound from the source of supply directly upon 10 and between the plates of the spring to be re-serviced, hereinafter described and then particularly pointed out in the appended claims.

The preferred form of the invention, together with certain modifications, is illustrated in the 15 accompanying drawing, in which:

Figure 1 is a view, in side elevation, of a portion of a spring equipped with a cover the cover being broken away from one side and the service tool having its injection head entered through 20 a hole in the cover and engaging the canvas liner;

Fig. 2 is a view similar to Fig. 1 showing the canvas liner pierced by the injection head of the 25 service tool;

Fig. 3 is a view, in vertical section, of the service tool;

Fig. 4 is an enlarged view, in elevation, of the injection head of the service tool;

Fig. 5 is a view similar to Fig. 4 but turned 90° 30 to show the face of the sheared thread and root;

Fig. 6 is a view, in elevation, of a modified form of the service tool;

Fig. 7 is a view, in plan, of the tool shown in 35 Fig. 6; and

Fig. 8 is a view, in elevation, like Fig. 4 but showing the modified buttress thread before shearing to the shape shown in Fig. 4.

In the embodiment of the invention illustrated 40 more particularly by Figs. 3, 4 and 5 of the drawing the service tool comprises a body 10 having an enlargement at one end forming a threaded socket 12 for receiving and retaining any standard greasing gun fitting. An axial duct 14 leads from the socket to the opposite end of the body. An 45 injection head 16 projects from this opposite end and if not made integral with the body may be retained in positioned in any convenient manner as by a force fit in the duct 14. The injection head, in its preferred form, is tubual and its axial duct 18 forms with the body duct 14 a continuous passage through the tool.

The free or working end of the injection head 50 has a special formation for piercing the fabric liner 20 (Figs. 1 and 2) that lies inside the spring-

cover 22 and, when the spring-cover is initially applied to the spring, is wrapped about the greased spring-plates 24. The spring-cover, if of metal, is provided with a hole 26 through which the injection head 16 is introduced. No hole is required in a fabric cover.

The working end of the hollow injection head is virtually a self-threading screw, in the preferred form of Figs. 4 and 5 but a valuable feature which is also embodied in the modified form of Fig. 6 is a helical formation adapted easily to thread itself through the liner and provided, for the purpose of breaking a hole in the fabric, with a spur-like terminal which obtains a grip on the rough fabric to bite into or tear through it on rotating the tool while pressed firmly against the outer face of the liner and holding it taut (see Fig. 1).

A simple and efficient way to form a spurred thread is to start with the modified buttress thread, for strength, illustrated in Fig. 8, two threads being sufficient. The end thread 30 is sheared axially at 32 through its root 34 to the shelf of the second thread. The end thread is also sheared along the helical thread shelf with a diagonal cut thereacross as indicated by the dot and dash lines 35 on Fig. 8. All of the dotted line portion of the end thread shown in Fig. 8 is thus removed and the single helical turn 36 then remaining, formed in part by the original first thread and in part by the second, has a lineal, instead of the original blunt, edge and, of essential importance here, is provided with a spur-like corner 38 (Figs. 4 and 5) at the top of the axial shear 32. The downward and outward slope of the helical shear is shown by the corner line 40 in Fig. 4. It is within the scope of the invention, as will be recognized by those skilled in the art, to produce this form of the injection head in other ways, for example, by die-casting in the desired shape. In this specification "shear" includes a facing formed by either cutting or pressure.

In the modified form of Figs. 6 and 7 in injection head 42 having the helical turn 44 providing a terminal spur 46 is preserved, the difference being that the tube forming the duct is itself twisted to a helix to enable the tool to grip the liner upon rotation while in contact therewith. A liner piercing end is formed by shearing through the tube at its free end, as clearly shown by Figs. 6 and 7, and this shear cut serves to produce a spur-like terminal 46.

Both forms embody the features of a hollow injection head having its working end sheared to form a spur-like terminal for piercing the liner when the tool is rotated while engaged with the liner. This is one important feature and while the helical form behind the spur facilitates entry of the injection head inside of the liner those skilled in the art may readily devise other forms which will be operative and which fall within the scope of this invention.

In both forms provision is made against injury to the spur-like end when the tool is laid on a bench. In the preferred form a collar 50 is provided of sufficient diameter to prevent the working end of the injection head from touching the bench. In the modified form the pointed end 46 is within the diameter of the helix 44 so that it may not contact the bench when the tool is laid on its side.

In operation, the injection head is entered through the hole 26 in a metal spring-cover and, after forcing the liner 20 inward until it is taut, is

then rotated (clockwise for the right-hand screw form illustrated) until the corner 38 or point 46 as the case may be engages and tears through the fabric. The end of the injection head immediately passes through the hole thus made and the broken liner lies back of the helix as shown in Fig. 2. A grease gun fitting having previously been screwed into the socket 12 the complementary fitting on the grease gun hose is placed thereover and the grease may then be pumped directly against the spring-plates 24. All danger of forcing grease between the liner and spring-cover has been eliminated. After the re-servicing operation is completed and the tool has been removed the hole 26 in the spring-cover may be closed by a plug button.

This application contains subject-matter of invention also disclosed in the co-pending application of Warren F. Eisenhauer and Warren T. Ferguson Serial No. 733,972, filed July 6, 1934 as 20 a continuation of their application Serial No. 685,566, filed August 17, 1933, but because said subject-matter, while necessary to the disclosure of the joint invention, is the sole invention of Eisenhauer, it is claimed only in this application. 25

The nature and scope of the invention having been indicated and its preferred and other embodiments having been specifically described, that which is claimed as new, is:—

1. A service tool, for re-servicing springs 30 equipped with a spring-cover having a liner, comprising a body, an injection head extending from one end of said body providing a helical formation adapted to enter a hole formed in the cover permitting engagement of the liner and functioning to thread itself through the liner upon rotating the tool, a socket at the other end of the body adapted to retain a grease gun fitting, and said tool having a continuous grease duct from said socket through said injection 40 head.

2. A service tool according to claim 1 in which said injection head is provided with a spur-like terminal for biting into the liner and forming a hole through which the injection head may be 45 entered by its rotation.

3. A service tool, for re-servicing springs equipped with a spring-cover having a liner, comprising a hollow body, a hollow injection head secured to one end of said body, said head 50 having at its working end a thread-like helix terminating in a spur-like shoulder for threading the head through said liner, and a socket at the other end of said hollow body for receiving a grease gun fitting.

4. A service tool, for re-servicing springs equipped with a spring-cover having a liner, comprising a hollow body, an injection head secured to one end of said body consisting of a tube of helical form having its free end shaped to 60 form a spur-like terminal for threading the head through said liner, and a socket at the other end of said hollow body for receiving a grease gun fitting.

5. In a service tool for the injection of a greasing compound within the lining of a lined spring-cover, a hollow injection head having its working end shaped to form a spur-like terminal for piercing the liner.

6. In a service tool for the injection of a greasing compound within the lining of a lined spring-cover, a tubular injection head having at least one thread at its working end and said thread being sheared axially through its root and also having its root cut away from the top 75

of said shear along the thread shelf to its bottom leaving an exposed section of the root.

7. A service tool as defined by claim 6 in which the said thread is a modified buttress having its upper face beveled outwardly to a lineal edge.

8. In a service tool for the injection of lubricant to the interior of a lined spring-cover, a hollow screw for piercing the spring-cover liner consisting of at least one thread at its working 10 end, said thread being sheared axially through the thread root.

9. In a service tool for the injection of lubricant to the interior of a lined spring-cover, a hollow body having an injection head and forming a duct for the passage of lubricant therethrough, said injection head having at least one screw thread and said thread presenting a longitudinal shear face at its end forming a piercing terminal at said end for biting into the 15 spring-cover liner.

10. A service tool, for re-servicing springs

equipped with a spring-cover having a liner, comprising a body providing a duct, and having an injection head extending from one end of said body providing a helical formation adapted to enter a hole formed in the cover permitting engagement of the liner and functioning to thread itself through the liner upon rotating the tool. 5

11. A service tool, for re-servicing springs equipped with a spring-cover having a liner, comprising a body providing a duct, and having an injection head extending from one end of said body providing a helical formation adapted to enter a hole formed in the cover permitting engagement of the liner and functioning to thread 10 itself through the liner upon rotating the tool, said duct having one end at said injection head 15 and being adapted for connection with grease supplying means at its other end.
